THIANAPHTHENE 1,1-DIOXIDE COMPOUNDS
Henry Blustone, University Heights, Ohio, assignor to
Diamond Alkali Company, Cleveland, Ohio, a corpora-
tion of DelawareNo Drawing. Filed Feb. 11, 1960. Ser. No. 7,982
6 Claims. (Cl. 260—332.1)

This invention relates to a novel class of biologically active compounds and to methods for preparing and using these compounds.

More specifically, the compounds of the present invention are pesticides having the generic formula

wherein Y is a bivalent radical selected from the group consisting of

and

R₁, R₂, R₃, R₄, R₅ and R₆ are selected from the group consisting of hydrogen and alkyl and X is halogen.

Exemplary of compounds falling within the above generic formula are the following:

(I)

3,3a-dichloro-3a,4,7,7a-tetrahydrothianaphthene 1,1-dioxide

(II)

3,3a-dichloro-3a,4,7,7a-tetrahydro-6-methylthianaphthene 1,1-dioxide

(III)

cis- and trans-3,3a,5,6-tetrachloro-3a,4,5,6,7,7a-hexahydrothianaphthene 1,1-dioxides

With regard to the material indicated as (II) above, it is not known for certain whether this has the structure shown or whether the methyl group is substituted in the five position, i.e.,

(V)

3,3a-dichloro-3a,4,7,7a-tetrahydro-5-methylthianaphthene 1,1-dioxide

In all probability, the material is a mixture of both the 5- and 6-methyl compounds. From a consideration of

2

the preparation reaction mechanism and the polarization of the reactants, it is believed that formation of the 6-methyl compound is favored. However, when reference is made hereinafter to the 6-methyl compound, it is to be understood that this is intended to include also the 5-methyl compound and mixtures of the 5- and 6-methyl compounds.

It is to be further noted that the compounds indicated hereinabove as (III) and (IV) are cis- and trans-isomers, having different melting points, although it is not known for certain which isomer is cis and which is trans. Additionally, as will be shown more fully hereinafter, the isomeric compounds also exhibit a different degree of biological activity and, more specifically, pesticidal activity.

15 In view of this, the cis- and trans-isomeric forms of this compound will hereinafter be treated as separate compounds.

It is to be understood, that as used hereinafter, the term "pesticide" or "pesticidal composition" is meant to 20 refer to those toxicant compositions which are effective in killing or controlling the growth of plants, insects, nematodes, microorganisms, fungi, bacteria and the like, and is intended to refer broadly to those compositions commonly known as insecticides, bactericides, fungicides, 25 nematocides, herbicides, and the like.

Additionally, the term "halogen," as used hereinafter, is intended to refer broadly to fluorine, chlorine, bromine, and iodine. However, because of its low cost and ready 30 availability, the preferred halogen in the compositions of the present invention is chlorine, and for this reason, primary reference hereinafter will be made thereto.

While compounds of this invention may be employed in a variety of applications, biologically active or otherwise, it will be understood, of course, that such compounds may 35 be utilized in diverse formulations, both liquid and solid, including finely-divided powders and granular materials, as well as liquids, such as solutions, concentrates, emulsifiable concentrates, slurries and the like, depending upon the application intended and the formulation media desired.

These compounds may be used alone or in combination with other known biologically active materials so as to provide a formulation which will be effective in controlling a variety of pests.

45 Thus, it will be appreciated that compounds of this invention may be employed to form biologically active substances containing such compounds as essential active ingredients thereof, which compositions may also include finely-divided dry or liquid diluents, extenders, fillers, conditioners, including various clays, diatomaceous earth, talc, spent catalyst, alumina-silica materials, liquids, solvents, diluents or the like, including water and various organic liquids, such as benzene, toluene, chlorinated benzene, acetone, cyclohexanone, xylene, carbon disulfide and various mixtures thereof.

When liquid formulations are employed, or dry materials prepared which are to be used in liquid form, it may be desirable in certain instances additionally to employ a wetting, emulsifying or dispersing agent to facilitate the use of the formulations, e.g., Triton X-155 (alkyl aryl polyether alcohol, U.S. Patent No. 2,504,064).

60 Additionally, it is to be understood that the term "carrier" as employed in the specification and claims hereof is intended to refer broadly to materials constituting a major proportion of a biologically active or other formulation, and hence includes finely-divided materials, both liquids and solids, as aforementioned, conveniently used in such applications.

In general, compounds of the present invention may 65 be prepared by combining a conjugated diene and a particular dienophile and causing them to react in a Diels-Alder reaction. The resulting product is then collected as

one of the compounds of the present invention or it may be subjected to further reaction, as for example, halogenation, to form other compounds of the present invention.

More specifically, a compound having the generic formula

and a compound having the generic formula

are combined in a Diels-Alder reaction so as to form a product having the generic formula

wherein the R groups are selected from the group consisting of hydrogen and alkyl and X is halogen. This product is then separated as a compound within the generic structure of the present invention or it may be further reacted as by halogenation to form other compounds falling within the generic formula of the present invention. The Diels-Alder reaction may be carried out in any suitable solvent, such as for example, methanol, and similarly, the halogenation of the Diels-Alder reaction product may also be carried out in a suitable solvent, such as chloroform. Moreover, the product of either the Diels-Alder reaction or of the halogenation reaction may be purified in any suitable manner, as for example, by distillation or by recrystallization from any suitable solvent, such as methanol.

In order that those skilled in the art can better understand the method of the present invention, and the manner in which it may be practiced, the following specific examples are given. In these examples, the 3,4-dichlorothiophene 1,1-dioxide is prepared according to the procedure set forth in U.S. application Ser. No. 709,449, now U.S. Patent 2,976,297. Moreover, the 3,3,4,4-tetrachlorotetrahydrothiophene 1,1-dioxide referred to in this preparation is prepared according to the method set forth in U.S. application Ser. No. 645,676, now U.S. Patent 2,957,887.

EXAMPLE 1

Preparation of 3,3a-Dichloro-3a,4,7,7a-Tetrahydrothianaphthene 1,1-Dioxide (I)

A solution of 46.3 g. (0.25 mole) of 3,4-dichlorothiophene 1,1-dioxide in 500 ml. of methanol is stirred and heated at 50° to 60° C. for five hours while 68.0 g. (1.26 mole) of butadiene is added. The methanol is then distilled off under vacuum. The residual liquid crystallizes when 100 ml. of petroleum ether are added, giving 21.2 g. crude (I). After recrystallization from methanol, this produces a first crop of 12.0 g. (20%) pure crystalline (I), M.P. 90° to 91° C., which has the following analysis:

Element	Calculated, percent by weight	Actual, percent by weight
C	40.2	40.1
H	3.38	3.38
Cl	29.6	30.3

EXAMPLE 2

A tomato foliage disease test is conducted measuring the ability of the product of Example 1 to protect tomato foliage against infection by the early blight fungus *Alter-*

naria solani. Tomato plants 5 to 7 inches high of the variety Bonny Best are employed. The plants are sprayed with 100 ml. of test formulation at 2000 p.p.m. and 400 p.p.m. test chemical in combination with 5% acetone—0.01% Triton X-155—and the balance water at 40 lbs. air pressure while being rotated on a turntable in a spray chamber. After the spray deposit is dry, the treated plants and comparable untreated controls are again sprayed as described above, with a sporangial suspension containing approximately 20,000 conidia of *A. solani* per ml. The plants are held in a 100% humid atmosphere for 24 hours at 70° F. to permit spore germination and infection. One day after removal from the humid atmosphere lesion counts are made on the three uppermost fully expanded leaves. Data based on the number of lesions obtained on the control plants shows 99% disease control at 2000 p.p.m. and 88% disease control at 400 p.p.m.

EXAMPLE 3

20 Fungicidal utility is further demonstrated by the ability of the product of Example 1 to protect tomato plants against the late blight fungus, *Phytophthora infestans*. The method employs tomato plants 5 to 7 inches high of the variety Bonny Best. 100 ml. of the test formulation (2000 p.p.m. and 400 p.p.m. of the test compound of Example 1, 5% acetone—0.01% Triton X-155—the balance water) are sprayed on the plants at 40 lbs. air pressure while the plants are being rotated on a turntable in a spray chamber. After the spray deposit is dry, the treated plants and comparable untreated controls are again sprayed as described above, with a sporangial suspension containing approximately 150,000 sporangia of *P. infestans* per ml. 30 seconds at 20 lbs. The plants are held in a 100% humid atmosphere for 24 hours at 60° F. to permit spore germination and infection. After 2 to 4 days, lesion counts are made on the three uppermost fully expanded leaves. Comparing the number of lesions on the test plants and control plants shows disease control of 94% and 68%, respectively, on the test plants.

EXAMPLE 4

In showing nematocidal activity of the product of Example 1, composted greenhouse soil in one-half gallon glazed crocks is infested with 3-5 g. of knotted or galled 45 tomato roots containing root knot nematodes, Meloidogyne species. Treatment at a rate equivalent to 256 lbs./acre (385 mg./crock) is effected by mixing the test chemical intimately with the soil. An indicator crop of three tomatoes are transplanted into treated crocks and 50 into infested and non-infested check crocks 4 to 7 days after treatment. The degree of infection which is measured by the number and size of galls formed compared to checks is used as an index of the nematocidal activity of the test material. Using the product of Example 1, results show no root knot infection.

EXAMPLE 5

The following test measures the ability of the product of Example 1 to protect pea seeds and seedlings from seed decay and damping off fungi (Pythium and Fusarium species). In this test, infested soil in 4 x 4 x 3 inch plant band box is treated by a soil drench-mix method at the equivalent rate of 32 lbs./acre. Treatment is accomplished by pouring 70 ml. of a 2000 p.p.m. test formulation (2000 p.p.m. of the product of Example 1, 5% acetone—0.01% Triton X-155—balance water) on the surface of the soil. This is allowed to stand until the next day when the soil is removed from each box and thoroughly mixed before being replaced in the box. Three days after treatment, 25 pea seeds, variety Perfection, are planted to a uniform depth per box. Untreated checks are included in each test in addition to a check planted in sterilized soil. Percentage stand recorded 14 days after planting shows 83% disease control.

5

EXAMPLE 6

The large seed leaves of 10-day old pinto bean plants, 4 plants per inch pot are used in this test. The product of Example 1 is applied to the soil in a test formulation (0.2% of the product of Example 1, 5% acetone, 0.01% Triton X-155, and the balance water). The concentrations of test chemical used are equivalent to 64 and 32 lbs./acre. Immediately following application of the test chemical to the soil surrounding the plants, the plants are sprayed with a spore suspension of the rust fungus, *Uromyces phaseoli*. This spore suspension is prepared by taking 30 mg. of freshly harvested spores and mixing with 48 mg. of talc. This is then diluted with water at the rate of about 1 mg. of the talc-spore mixture to 1.7 ml. of distilled water.

After spraying the spores on the seed leaves of the bean plants, they are placed in a water saturated atmosphere for 24 hours at 60° F. After incubation the plants are removed to controlled greenhouse conditions and 9-10 days after exposure rust lesions are counted. The data observed is converted to percentage disease control based on the number of lesions obtained on untreated control plants. Using this procedure, results indicate 95 and 85% disease control, respectively, for the two concentrations used.

EXAMPLE 7

Preparation of 3,3a-Dichloro-3a,4,7,7a-Tetrahydro-5 and/or 6-Methylthianaphthene 1,1-Dioxide (II) and/or (V)

A solution of 111.0 g. (0.6 mole) 3,4-dichlorothiophene-1,1-dioxide in 1360 ml. methanol is stirred at 45° to 55° C. while 68.0 g. (1.0 mole) of isoprene is added slowly. Stirring is continued for an hour, then a second mole of isoprene is added and stirring at 50° C. is continued for three more hours. The solution is left overnight at room temperature and then distilled. The 48.2 g. of crude liquid which distills above 90° C. at 0.8 mm. is redistilled, yielding 29.5 g. (19%) of pale yellow (II) and/or (V) between 133° and 136° C. at 0.6 mm. This has a refractive index (N_D^{25}) of 1.5550 and a density (D_4^{25}) of 1.4215.

Element	Calculated, percent by weight	Actual, percent by weight
C	42.8	43.2
H	3.98	3.87
S	Present	Present

EXAMPLE 8

Tomato plants, variety Bonny Best, growing in 4" pots are treated by pouring a test formulation (2000 p.p.m. of the product of Example 7, 5% acetone—0.01% Triton X-155—balance water) into the pots at an equivalent rate of 128 lbs./acre (102 mg./pot). The tomato plants are 3 to 4" tall with the trifoliate leaves just starting to unfold at time of treatment. The plants are exposed to powdery mildew continuously after seedling emergence so that at the time of treatment infection has occurred. After 10 to 14 days, observation indicates 97% disease control by comparison to untreated control plants.

EXAMPLE 9

In order to make an *in vitro* evaluation of the product of Example 7 as a contact nematocide, nematodes (*Panagrellus redivivus*), are exposed to the test chemical in small watch glasses (27 mm. diameter x 8 mm. deep), within a 9 cm. Petri dish. An aqueous test formulation (1000 p.p.m. of the product of Example 7—5% acetone—0.01% Triton X-155—balance water) is used. Results are recorded 24 hours after treatment and from these it is shown that 100% mortality is observed.

EXAMPLE 10

The product of Example 7 is tested using the fungicide

6

evaluation procedure of Example 6. The concentration of the test chemical used is equivalent to 64 lbs./acre and the results obtained show 93% disease control.

EXAMPLE 11

Preparation of Cis- and Trans-3,3a,5,6-Tetrachloro-3a,4,5,6,7,7a-Hexahydrothianaphthene 1,1-Dioxides (III) and (IV)

A solution of 30.0 g. (0.125 mole), 3,3-dichloro-3a,4,7,7a-tetrahydrothianaphthene 1,1-dioxide (the product of Example 1) in 100 ml. of chloroform is stirred while 13.2 g. (0.186 mole) chlorine is added during nineteen minutes at a maximum temperature of 58° C. The solvent is removed under reduced pressure, leaving 39.1 g. of a colorless viscous liquid. Triturating with methanol induces crystallization of 1.5 g. white solid. Repeated fractional crystallization of this solid from methanol produces both tetragonal plates, M.P. 140° to 141° C. and needle-shaped crystals M.P. 180.5° to 182.5° C. Chlorine determinations shows these to be cis- and trans-isomers of the desired tetrachloro compound. The lower melting product (III) is believed to have a cis arrangement of the chlorine atoms at the 5 and 6 positions and the higher melting isomer (IV) is believed to have the trans configuration.

Compound:	Found
III	M.P. 140°-141° C., Cl, 45.7%.
IV	M.P. 180.5°-182.5° C., Cl, 45.4%.
Calculated	Cl, 45.7%.

Concentration, p.p.m.:	Percent disease control
512	100
256	100
128	100
64	99
32	66

EXAMPLE 12

Product III of Example 11 is tested using the fungicide evaluation procedure of Example 2. The concentrations used and the results obtained are as follows.

Concentration, p.p.m.:	Percent disease control
512	100
256	100
128	100
64	99
32	66

EXAMPLE 13

Product III of Example 11 is tested using the fungicide evaluation procedure of Example 3. The concentrations used and the results obtained are as follows.

Concentration, p.p.m.:	Percent disease control
512	100
256	100
128	100
64	99

EXAMPLE 14

Product III of Example 11 is tested using the fungicide evaluation procedure of Example 6. The concentration used is equivalent to 64 lbs./acre and the results show 69% disease control.

Concentration, p.p.m.:	Percent disease control
512	100
256	100
128	100
64	99

EXAMPLE 15

Using the large seed leaves of 10-day old pinto bean plants, a test formulation made up of (0.2% of product III of Example 11, 5% acetone—0.01% Triton X-155—balance water) is sprayed on the foliage of the plants, and allowed to dry. Thereafter, the plants are exposed to uredospores of the bean rust fungus, *Uromyces phaseoli*. Thus exposed seed leaves of bean plants are then placed in a saturated atmosphere for 24 hours at 60° F. After incubation the plants are removed to controlled greenhouse conditions and 9 to 10 days after exposure, rust lesions are counted. The data observed is converted to percentage disease control based on the number of lesions obtained on the control plants. The concentration of product III of Example 11 is 512 p.p.m. and the results obtained show 82% rust control.

EXAMPLE 16

Product IV of Example 11 is tested using the fungicide evaluation procedure of Example 2. The concentrations used and the results obtained are as follows.

Concentration, p.p.m.	Percent disease control
512	83
256	74
128	70
64	62 10

From a comparison of Examples 12 and 16, it is seen that although both the cis- and trans-isomers possess fungicidal properties, III is more active. Additionally, as seen from Example 14, III possesses systemic fungicidal activity; in this area, IV is completely ineffective.

While there have been described various embodiments of the invention, the methods and products described are not intended to be understood as limiting the scope of the invention, as it is realized that changes therein are possible and it is further intended that each element recited in any of the following claims is to be understood as referring to all equivalent elements for accomplishing substantially the same results in substantially the same or equivalent manner, it being intended to cover the invention in whatever form its principle may be utilized.

What is claimed is:

1. The compound having the formula

5

wherein Y is a bivalent radical selected from the group consisting of

and

R₁, R₂, R₃, R₄, R₅ and R₆ are selected from the group consisting of hydrogen and methyl and X is halogen.

2. 3,3a - dichloro - 3a,4,7,7a - tetrahydrothianaphthene 1,1-dioxide.

3. 3,3a-dichloro - 3a,4,7,7a - tetrahydro - 6 - methylthianaphthene 1,1-dioxide.

4. Cis - 3,3a,5,6 - tetrachloro - 3a,4,5,6,7,7a - hexahydrothianaphthene 1,1-dioxide.

5. Trans - 3,3a,5,6 - tetrachloro - 3a,4,5,6,7,7a - hexahydrothianaphthene 1,1-dioxide.

6. 3,3a - dichloro - 3a,4,7,7a - tetrahydro - 5 - methylthianaphthene 1,1-dioxide.
